(57) ABSTRACT

A new and distinct *Syringa* cultivar named 'SMSDTL' is disclosed, characterized by a distinctive compact, dwarf habit. Plants produce attractive foliage and lavender flowers. The new variety is a *Syringa* normally produced as an outdoor garden or container plant.

2 Drawing Sheets

1

Latin name of the genus and species: *Syringa debelder*.
Variety denomination: 'SMSDTL'.

BACKGROUND OF THE INVENTION

The present invention comprises a new and distinct variety of *Syringa*, hereinafter referred to by the cultivar name 'SMSDTL'. This new *Syringa* was developed through a breeding program in Grand Haven, Mich. The objective of the breeding program was to develop new *Syringa* colors and forms. 'SMSDTL' is an internal advanced selection from an in-house breeding program. The seed parent is an unnamed, unpatented selection of *Syringa pubescens* subsp. *patula*. The pollen parent is unidentified as the new variety was produced through an open pollination breeding program. The open pollination resulting in the new variety was made in Spring of 2005. Selection of the new variety was made in May 2007.

The first asexual propagation of 'SMSDTL' was carried out in June 2007 by softwood cuttings at a commercial nursery in Grand Haven, Mich. 'SMSDTL' has been found to retain its distinctive characteristics through successive asexual propagations. Multiple generations have been propagated, with the new variety characteristics reproduced true to type.

SUMMARY OF THE INVENTION

The following are the most outstanding and distinguishing characteristics of this new cultivar when grown under standard horticultural practices at Grand Haven, Mich.:

1. More dwarf than other *Syringa* varieties.
2. Compact habit.
3. Attractive foliage.
4. Lavender flowers.

COMPARISON WITH THE PARENT VARIETIES

'SMSDTL' is similar to the seed parent, in most horticultural characteristics. 'SMSDTL' however differs in the following:

2

1. The new variety is a more dwarf plant than the seed parent.
2. The new variety has light lavender flowers, while the seed parent has more purple flowers.

COMMERCIAL COMPARISON

'SMSDTL' is similar to the unpatented commercial variety *Syringa patula* 'Miss Kim', in most horticultural characteristics. 'SMSDTL' however differs in the following:

1. Plants of the new variety are more dwarf, while this comparator is a larger, rangier plant.
2. New variety has light lavender flowers, while this comparator has lavender blue flowers.

DESCRIPTION OF THE PHOTOGRAPHS

This new *Syringa* is illustrated by the accompanying photographs which show the plant's form, foliage and inflorescences. The colors shown are as true as can be reasonably obtained by conventional photographic procedures. Plants were grown in Grand Haven, Mich.

FIG. 1. Shows a flowering plant of 'SMSDTL' in the ground at approximately 3 years old during Summer.

FIG. 2. Shows a close-up view of the inflorescence.

DESCRIPTION OF THE NEW CULTIVAR

- 30 In the following description, color references are made to The Royal Horticultural Society Colour Chart 2015 except where general terms of ordinary dictionary significance are used. The following observations and measurements describe 'SMSDTL' plants grown in a poly-greenhouse 35 during Summer, in Grand Haven, Mich. The growing temperature ranged from 18° C. to 27° C. during the day and from 5° C. to 10° C. during the night. General light conditions are natural sunlight. Measurements and numerical values represent averages of typical plant types.

DETAILED BOTANICAL DESCRIPTION

Botanical classification: <i>Syringa debelderii</i> 'SMSDTL'.		Flowers per lateral stem.—Over 1000.
Propagation:		Flower diameter.—5 mm.
Typical method: Softwood cuttings.	5	Flower depth.—5 mm.
Time to initiate rooting: About 20 days at approximately 18° C. to 27° C.		Flower throat diameter.—2 mm.
Time to produce a rooted young plant: About 3 months at approximately 18° C. to 27° C.		Flower tube diameter (base).—1 mm.
Root description: Dense, free branching, thin, fibrous. Colored white, not accurately measured with an R.H.S. chart.	10	Flower tube length.—4 mm.
Plant description:		Flower angle.—Upright, outward and drooping.
Age of plant described.—2 to 3 years in a 3 gallon container.		Persistence.—Self-Cleaning.
Plant shape.—Perennial shrub. Rounded.	15	Flower bud:
Growth habit.—Upwards and outwards.		Buds per lateral stem.—Over 1000.
Height.—69 cm.		Length.—6 mm.
Width.—95 cm.		Diameter.—2 mm.
Growth rate.—Good.	20	Shape.—Obovate.
Plant vigor.—Moderate.		Color.—RHS White N155A.
Branches:		Petals:
Branching habit.—Upwards and outwards.		Number.—4.
Lateral branch quantity.—50.		Arrangement.—Rotate.
Lateral branch length.—56 cm.	25	Length.—1 mm.
Lateral branch diameter.—5 mm.		Width.—1 mm.
Branch aspect.—Upwards.		Shape.—Ovate.
Branch strength.—Good.		Apex.—Acute, slightly recurved.
Branch color.—New growth: RHS Green 143B. Old growth: Close to RHS Greyed-Green 197A.	30	Margin.—Entire.
Internode length.—3 cm.		Texture.—Soft, smooth, delicate.
Foliage:		Throat texture.—Smooth.
Leaves:		Tube texture.—Smooth.
Arrangement.—Opposite.		Color.—Immature upper surface: RHS Red-Purple 69D. Immature lower surface: RHS Purple 75A and Yellow 10A. Mature upper surface: RHS White NN155C. Mature lower surface: RHS White NN155C.
Length.—4 cm.		Flower tube (interior).—Mix of RHS Purple 75A and White NN155C.
Width.—5.5 cm.		Flower throat (exterior).—RHS White NN155C.
Shape.—Ovate.	35	Sepals: Inconspicuous and extremely reduced. Too minute (less than 1 mm by 1 mm in size) for accurate measurement.
Apex.—Acute.		Peduncle:
Base.—Obtuse.		Length.—5 cm.
Margin.—Entire.		Width.—2 mm.
Texture upper surface.—Soft.	40	Color.—RHS Green 138A.
Texture lower surface.—Soft, distinct veins.		Texture.—Smooth.
Color.—Immature: Upper: RHS Yellow-Green 144A. Lower: RHS Yellow-Green 144A. Mature: Upper: RHS Green 137A. Lower: RHS Green 138A.		Angle.—Upright/outward.
Venation:		Strength.—Good.
Pattern.—Pinnate.	45	Pedicels:
Color.—Upper: RHS Yellow-Green 144C. Lower: RHS Yellow-Green 144C.		Length.—3-5 mm.
Petiole:		Diameter.—1 mm.
Length.—1.5 cm.		Texture.—Smooth, pubescent.
Width.—2 mm.	50	Color.—RHS Green 138A.
Texture.—Smooth.		Strength.—Good.
Color.—Upper side: RHS Yellow-Green 144C. Under side: RHS Yellow-Green 144C.		Angle.—Upright/outward.
Inflorescence:		Reproductive organs:
Description.—Bunches of panicles.		Gynoecium:
Flowering season.—Spring.		Pistil number.—1.
Fragrance.—Moderately strong, floral.		Pistil length.—3 mm.
Inflorescence type.—Panicles.		Stigma shape.—Oblong to rounded.
Number of flowers per inflorescence.—75-100.	55	Stigma color.—Close to RHS White 155A.
Inflorescence height.—12.5 cm.		Style length.—About 2 mm.
Inflorescence diameter.—4.5 cm.		Style color.—Close to RHS White 155A.
Flowers:	60	Androecium:
Flower type.—Funnelform/salverform.		Stamen number.—2.
Flowering habit.—Terminal and axial on the panicles.	65	Filament length.—1.5 mm.
		Filament color.—RHS White NN155C.
		Anther shape.—Oblong.
		Anther length.—2 mm.
		Anther color.—RHS Grey 201A.

US PP31,830 P2

5

Amount of pollen.—Some.

Pollen color.—RHS Green-Yellow 1A.

OTHER CHARACTERISTICS

Fruit: Not observed to date.

Disease and insect resistance: No significant disease or pest resistance nor susceptibility have been observed.

6

Temperature range: Observed to tolerate temperatures between -33° C. and 36° C.

What is claimed is:

5 1. A new and distinct *Syringa* named 'SMSDTL' as illustrated and described herein.
